United States Patent Office.

JOHN L. LAY, OF BUFFALO, NEW YORK, ASSIGNOR TO HIMSELF AND
H. O. PERRY, OF SAME PLACE.

Letters Patent No. 66,974, dated July 23, 1867.

IMPROVEMENT IN STEAM ENGINES.

The Schedule referred to in these Letters Patent and making part of the same.

TO ALL WHOM IT MAY CONCERN:

Be it known that I, JOHN L. LAY, of the city of Buffalo, in the county of Erie, and State of New York, have invented certain improvements in the Method of Supporting the Cylinders of Vertical Steam Engines; and I do hereby declare that the following is a full and exact description thereof, reference being had to the accompanying drawings, making part of this specification, in which—

Figure 1 is a side elevation of a high and a low-pressure cylinder, arranged vertically, with the supporting frame partially in section.

Figure 2 is a horizontal section in the plane of the line $x x$, fig. 1.

Figure 3 is a modification of my improvement.

Like letters designate corresponding parts in all the figures.

My invention consists of the means hereinafter described of supporting the cylinders of vertical engines.

In the drawings, A A represents three or more standards firmly fastened to a base-plate, B, preferably by bolts through flanges a at their foot, which converge or incline towards each other at the top, their upper ends being secured to a cap or horizontal frame, C, as shown in fig. 1. These standards I prefer to make of iron, (although other material may be employed,) of the angular form shown by the cross-section in fig. 2. To these standards are bolted brackets D D, the arms of which project inward and support the cylinder E which rests upon them, as shown in figs. 1 and 2, being bolted or otherwise fastened thereto. Under the ends of each of the brackets I employ a vertical post or column, G, which renders the support more firm where the cylinder is of large size. F represents the high-pressure cylinder, cast with three or more flanges $g g$ (fig. 1) which rest upon and are bolted to the top of a corresponding number of standards H H, similar to A A, which are firmly bolted to the cap-plate C, as shown. The cylinder E may be provided with flanges similar to those of a high-pressure cylinder, and be bolted to the brackets D, or it may be cast with a flange, g' , surrounding it, and be arranged within and bolted to the top plate C of frame A A, as represented in fig. 3. If preferred the ends of the bracket-arms may be connected by an annular plate, upon which rests and is fastened the cylinder, the columns being employed as represented, the effect being substantially the same as when the brackets are disconnected from each other, the flange of the cylinder in that case performing the same office as the annular plate. It is evident that the standards A may be made sufficiently high to support the cylinder F at their top, while the cylinder E is sustained as represented in fig. 1. This arrangement of the converging standards and their adjuncts gives great steadiness and stability to the engine by bracing it equally in every direction, and obviates much of the jar and vibration which have an injurious effect on engines of this construction, where a single rod carries the two cylinders placed in a line. It also admits of their more convenient adjustment to a true working line than when otherwise arranged and supported.

What I claim as my invention is—

frame for supporting the cylinders E F of vertical compound engines, composed of the converging standards A A and H H, cap or intermediate plate C, flanges $g g$, and brackets D D or equivalent, with the pillars G G, combined and arranged substantially in the manner and for the purpose set forth.

In witness whereof I have hereunto signed my name in the presence of two subscribing witnesses.

JOHN L. LAY.
